Primary Examiner—Philip S. Hyder*Attorney, Agent, or Firm*—Barrigar & Moss**[57] CLAIM**

The ornamental design for a portable storage container, as shown and described.

DESCRIPTION

FIG. 1 is a perspective view of a first embodiment of the design;

FIG. 2 is a left side elevational view of the first embodiment of the design, the right side being identical in appearance; FIG. 3 is an end elevational view of the first embodiment of the design, each end having the same appearance;

FIG. 4 is a top view of the first embodiment of the design; FIG. 5 is a bottom view of the first embodiment of the design;

FIG. 6 is a perspective view of a second embodiment of the design;

FIG. 7 is a left side elevational view of the second embodiment of the design, the right side being identical in appearance;

FIG. 8 is an end elevational view of the second embodiment of the design, each end having the same appearance;

FIG. 9 is a top view of the second embodiment of the design; and,

FIG. 10 is a bottom view of the second embodiment of the design.
